UNITED STATES PATENT OFFICE.

JAMES W. HAMILTON, OF BROOKLYN, NEW YORK.

METHOD OF AND APPARATUS FOR CONSTRUCTING TUNNELS.

1,275,910.

Specification of Letters Patent. Patented Aug. 13, 1918.

Application filed August 31, 1916. Serial No. 117,966.

To all whom it may concern:

Be it known that I, JAMES WATT HAMILTON, a citizen of the United States, and resident of Brooklyn, county of Kings, city and State of New York, have invented certain new and useful Improvements in Methods of and Apparatus for Constructing Tunnels, of which the following is a specification.

10 This invention relates more particularly to improvements in that method of constructing tunnels in which a shield is forced forward into the earth to be excavated, the earth within the shield being then removed 15 and the shield again thrust forward. In this method of constructing tunnels there is of necessity a considerable area of roof or top of the tunnel unprotected and uncovered. When operating under this method in 20 places requiring air pressure to hold back water and prevent it flowing into the tunnel, it frequently happens that the air forces itself through the unprotected earth. There is nearly always a very serious air leakage 25 through the tunnel roof when working with the shield method.

It is one of the main objects of this invention to provide a sectional sheet metal shield for the tunnel, or so much thereof as 30 may be found necessary or desirable, and to provide means for driving or forcing said sheet metal sections forwardly into the earth to be excavated. Each of the sections is to be driven independently; and the said sec- 35 tional shield is to be of such length as to completely cover the tunnel roof and to extend from the completed permanent lining into the earth beyond what is termed the heading or earth wall at the end of the ex- 40 cavated portion of the tunnel.

Another object of the invention is to provide a method of constructing tunnels which consists primarily in providing a sectional metal shield for the tunnel, or a portion 45 thereof, driving the said sectional shield into the earth a suitable distance, excavating a portion of the earth inclosed by said sectional shield; constructing the permanent tunnel lining at the rear ends of the said sheet 50 metal sectional shield and then again forcing forward the sectional shield the desired distance without freeing the rear end thereof from the completed permanent tunnel lining, whereby a substantially air tight cov- 55 ering will at all times be provided for the tunnel section between the completed tunnel

lining and the earth wall at the end of the excavation.

Another object of the invention is to provide means for driving forward each metal 60 section independently, the driving means being suitably mounted to permit it to be moved from one metal section to the next during the driving operation.

Another object of the invention is to pro- 65 vide a sheet metal sectional shield for a tunnel, the sections being interlocked along their longitudinal edges in the manner of interlocking sheet metal pilings; and to provide means whereby each metal section may 70 be independently driven or forced into the earth to be excavated.

Another object of the invention is to pro- 75 vide a power hammer for driving the sheet metal sectional shield, said hammer being provided with means for yieldingly holding it against the end of the shield section, whereby it will follow the said section as it is driven.

There are other important objects and ad- 80 vantages of the invention which will appear hereinafter.

In the drawings, Figure 1 is a vertical, longitudinal sectional view of the appa- 85 ratus;

Fig. 2, an end view thereof;

Fig. 3, a longitudinal, vertical, sectional view showing one method of constructing tunnels in accordance with this invention; 90 and

Fig. 4 is a similar view showing a slightly modified method of operating in accordance with this invention.

Referring to the various parts by numerals, 1 designates the sheet metal sections 95 which constitute the shield or cutter which is designed to be driven forward into the earth to be excavated. These sheet metal sections are formed along their longitudinal edges with interlocking ribs and flanges, the rib on one section fitting within the flanges on the adjoining section, in the manner of the well known sheet metal piling. These sections are arranged in a horizontal position and they are interlocked at their edges 100 to form a semi-cylindrical shield as indicated clearly in Figs. 1 and 2. It is manifest of course, that the interlocked sheet metal sections may be arranged as a shield of any desired shape or size in cross section. As 110 shown in Figs. 1 and 2, the sheet metal sections rest on a semi-circular form 2, which

is mounted upon a truck 3. It is manifest that the form may be of any desired shape and that the interlocked sheet metal sections may be readily conformed to said shape.

5 As shown in Figs. 1 and 2, two power hammers 4 are mounted upon swinging booms 5, said booms being pivoted to the center of the truck. In order to swing the hammer booms to bring the hammers in 10 proper position to engage the sheet metal sections, said booms are provided with hoisting cables 6 which pass over hoisting drums 7. The hoisting drums may be of any suitable form. As the hammer booms are pivoted 15 at substantially the center of the truck 3, they may be swung to bring the hammers into engagement with the ends of the metal sections, as clearly illustrated in Fig. 2. The hammers are adapted to be operated by 20 fluid pressure entering the cylinders 9 thereof through supply pipes 10. Any suitable form of power hammer may be employed, and I, therefore, have not shown the hammer 4 in detail. Each hammer is mounted 25 upon a table 11, supported at the outer end of its boom 5. Each hammer is provided with longitudinally extending guide flanges 12 which engage guides 13 mounted on the table 11. On each table 11 is mounted a 30 cylinder 14 in which is arranged a piston 15, said piston being connected to the hammer frame by a piston rod 16. Pipes 17 are connected to said cylinder near the ends thereof to admit fluid pressure on opposite 35 sides of the piston 15. It is manifest that by permitting pressure on one side of the piston the hammer will be forced forward and caused to follow the metal section which it is driving. It is also manifest that by 40 admitting fluid pressure to the other side of the piston it will withdraw the hammer from engagement with the sheet metal section.

The ends of the form 2 are connected to 45 the truck 3 by means of turnbuckles and rods 19. The truck 3 is supported on adjusting screws 20, so that said truck may be raised and lowered as desired. By means of the turn-buckles and rods 19 and adjusting 50 screws 20, the form 2 may be slightly contracted or drawn inwardly from the sheet metal sections, and then may be lowered by means of the adjusting screws 20, thus permitting the truck 3 and the apparatus carried thereby to be moved forward into the 55 tunnel. After the adjustment of the truck to the proper position in relation to the sectional sheet metal shield the turnbuckles and rods 19 may be extended and the entire truck 60 may be raised slightly to bring the entire form into engagement with the shield. The truck 3 may then be braced by blocks 21 or in any other suitable manner.

It is manifest from the foregoing that the 65 hammers may be brought into engagement

with each one of the sheet metal sections and that each section may be individually driven forward the desired distance. Any suitable form or guide for the sheet metal sections may be employed and the said sections may be of any desired size and of any suitable construction. It is desirable that their longitudinal edges be interlocked as indicated clearly in Fig. 2 of the drawings so as to form a continuous interconnected metal 70 shield for the roof of the tunnel. It is obvious that the sheet metal sectional shield may be made to cover as much of the tunnel roof as may be found necessary or desirable. 75

In Fig. 3, the sheet metal sections are each 80 provided with a driving head 22, said head being connected to the section at a suitable point between the ends thereof and extending inwardly and projecting into the tunnel. This driving head is adapted to be engaged 85 by the hammer as shown clearly in this figure. In this method of operation the sheet metal sections are of such a length that they extend from the completed tunnel lining 23 a suitable distance into the earth to be excavated. 90 The object of this is to provide a complete interlocked metal lining for the tunnel excavation between the completed permanent tunnel lining 23 and the earth wall 24 at the head end of the tunnel. In 95 operating under this method the sheet metal shield sections are never free of the permanent tunnel lining. After the shield has been driven forward the desired distance, the earth within the shield is excavated and 100 the driving apparatus then moved forward to again engage the driving heads 22. A section of permanent lining is then placed in position, said permanent lining extending a suitable distance along the sheet metal sections. The said metal sections are then 105 again driven forward into the earth and a further excavation made. The driving apparatus is again moved forward and an additional portion of permanent lining formed. 110 In this way the tunneling operation proceeds, a complete sheet metal lining being at all times provided for the excavation between the permanent tunnel lining and the earth wall at the head end of the tunnel. 115

In Fig. 4, a method of constructing a tunnel is illustrated in which the sheet metal sections remain as a part of the permanent tunnel lining. As shown in this view the metal sections are driven into the earth a 120 suitable distance and are permitted to remain permanently in position, the additional metal sections being driven in overlapping relation to the sections previously driven. In this way a permanent sheet metal sectional lining is provided outside of the permanent tunnel lining. 125

This invention consists, in its broad aspects, in providing a sheet metal sectional shield wherein the individual sections are 130

capable of independent longitudinal movement. It is desirable that these independent sections be interlocked along their longitudinal edges so they will maintain their 5 alinement and proper relation throughout their entire longitudinal movement.

By providing a tunnel shield of the character described each individual section or plate may be driven forward into the earth 10 to be excavated with a very slight expenditure of power as compared with the great power required to drive the very large cutters used in the old shield method of tunneling.

15 What I claim is:—

1. A tunneling apparatus comprising a shield formed of a plurality of independently movable longitudinal sections, a horizontally arranged power hammer for driving 20 said sections, and means for shifting said hammer to adapt it to engage each of said sections.

2. A tunneling apparatus comprising a shield formed of a plurality of independently movable longitudinal sections, a horizontally arranged power hammer for driving 25 said sections, means for shifting said hammer to adapt it to engage each of said sections, and means for maintaining the 30 hammer in operative relation to the sections as the said sections are driven forwardly.

3. A tunneling apparatus comprising a shield formed of a plurality of independently movable longitudinal sections, a horizontally arranged power hammer for driving 35 said sections, means for shifting said hammer to adapt it to engage each of said sections, and yieldable means for maintaining the power hammer in operative relation 40 to the section on which the hammer is operating.

4. A tunneling apparatus comprising a shield formed of a plurality of independently movable longitudinal sections, a horizontally arranged power hammer for driving 45 said sections, means for shifting said hammer to adapt it to engage each of said sections, a fluid pressure device engaging the hammer and forcing it into engagement 50 with the section on which the hammer is operating.

5. A tunneling apparatus comprising a shield formed of a plurality of independently movable longitudinal sections, a power 55 hammer, means for supporting said hammer, said means being movable to permit the said hammer to be brought into engagement with each of said longitudinal sections and means for moving said hammer bodily forward 60 to maintain it in engagement with the section on which it is operating.

6. A tunneling apparatus comprising a shield formed of a plurality of independently movable longitudinal sections, a power 65 hammer, means for supporting said ham-

mer, said means being movable to permit the said hammer to be brought into engagement with each of said longitudinal sections, a fluid pressure device for bodily moving the hammer forwardly to maintain it in operative relation to the section on which the hammer is operating. 70

7. A tunneling apparatus comprising a shield formed of a plurality of independently movable longitudinal sections, a movable truck, a form carried by said truck and adapted to support one end of the shield, a power hammer mounted on said truck and means for moving said hammer to bring it into engagement with the longitudinal sections. 75

8. A tunneling apparatus comprising a shield formed of a plurality of independently movable longitudinal sections, a movable truck, a collapsible form carried by 80 said truck and adapted to support one end of the shield, a power hammer mounted on said truck and means for moving said hammer to bring it into engagement with the longitudinal sections. 85

9. A tunneling apparatus comprising a shield formed of a plurality of independently movable longitudinal sections, a movable truck, a form carried by said truck and adapted to support one end of the shield, a power hammer mounted on said truck and means for moving said hammer to bring 90 it into engagement with the longitudinal sections, and movable means for maintaining the hammer in operative relation to the section on which it is operating. 100

10. A tunneling apparatus comprising a shield formed of a plurality of independently movable longitudinal sections, a movable truck, a form carried by said truck and adapted to support one end of the shield, a power hammer mounted on said truck and means for moving said hammer to bring it into engagement with the longitudinal sections, a fluid pressure device for maintaining the hammer in operative relation to 105 the section on which it is operating. 110

11. A tunneling apparatus comprising a shield formed of a plurality of independently movable longitudinal sections, means 115 for interlocking the longitudinal edges of said sections, a power hammer, means for supporting said hammer in a horizontal position, means for moving said hammer to adapt it to engage the said sections and 120 yieldable means for moving said hammer longitudinally to cause it to follow the section being driven. 120

12. A tunneling apparatus comprising a movable support, a shield, a form carried by 125 the support for sustaining one end of said shield, a swinging frame pivotally mounted on the support to rock transversely of the shield, and means supported on said frame for driving said shield. 130

13. A tunneling apparatus comprising a movable support, a shield, a form carried by the support for sustaining one end of said shield, a swinging frame pivotally mounted on the support to rock transversely of the shield, a power hammer supported on said frame for driving the shield, and means for advancing the hammer bodily toward the shield as the shield is driven forwardly thereby. 35
14. A tunneling apparatus comprising a movable support, a shield, a form carried by the support for sustaining one end of said shield, a swinging frame pivotally mounted on the support to rock transversely of the shield, a power hammer slidably supported in said frame for movement bodily toward and from the shield, and fluid pressure means mounted on the frame for advancing the hammer as the shield is driven forwardly thereby. 40
15. A tunneling apparatus comprising a movable truck, an arcuate form mounted on said truck, means for raising and lowering said form, an arcuate shield comprising independently movable longitudinal sections flexibly and slidably connected with each other and supported on said form, a power hammer, a shiftable support for said hammer mounted on the truck, and means for shifting said support to position the hammer to drive successive shield sections. 45
16. A tunneling apparatus comprising a movable truck, an arcuate form mounted on 50

said truck, a shield comprising independently movable longitudinal sections flexibly and slidably connected together and supported on said form, a power hammer, and a swinging support for the power hammer pivotally mounted on the truck at a point coincident with the axis of the arc of the form. 55

17. A tunneling apparatus comprising a movable truck, an arcuate form mounted on said truck, a shield comprising independently movable longitudinal sections supported on said form, a power hammer, a support for the hammer pivotally mounted on the truck at a point coincident with the axis of the arc of the form, and means for swinging said support to position the hammer to drive successive shield sections. 60

18. A tunneling apparatus comprising a movable truck, an arcuate form mounted on said truck, a shield comprising independently movable longitudinal sections supported on said form, two power hammers, independently shiftable supports for said hammers pivotally mounted on the truck at a point coincident with the axis of the arc of the form, independent means for swinging said supports to position each of the hammers to drive sections of the shield, and means for maintaining each hammer support in its adjusted position. 65

In testimony whereof I hereunto affix my signature.

JAMES W. HAMILTON.
